UNITED STATES PATENT OFFICE.

CHARLOTTE D. ORCUTT, OF BOSTON, MASSACHUSETTS, ASSIGNOR OF ONE-FOURTH TO MARY LOUISE EVERETT, OF CONCORD, MASSACHUSETTS.

FUEL-RECEPTACLE FOR COOKING-STOVES.

SPECIFICATION forming part of Letters Patent No. 685,484, dated October 29, 1901.

Application filed November 10, 1900. Serial No. 36,097. (No model.)

To all whom it may concern:

Be it known that I, CHARLOTTE D. ORCUTT, of Boston, in the county of Suffolk and State of Massachusetts, have invented certain new and useful Improvements in Fuel-Receptacles for Cooking-Stoves, of which the following is a specification.

This invention has for its object to provide a fuel-receptacle which can be applied to and removed from the fire-box of a cooking-stove, and is adapted to hold a relatively small quantity of fuel near the top of the stove, to the end that the fuel may be economized by maintaining a shallow bed of fuel in close proximity to the top of the stove, the receptacle being removed from the stove when it is desirable to support the fuel on the ordinary grate of the fire-box in the usual way.

The invention consists in the improvements which I will now proceed to describe and claim.

Of the accompanying drawings, forming a part of this specification, Figure 1 represents a perspective view of a fuel-receptacle embodying my invention. Fig. 2 represents a transverse vertical section of the same, showing it in place in the fire-box of a cooking-stove.

The same reference characters indicate the same parts in both the figures.

My improved fuel-receptacle is a relatively shallow basket *a*, formed to be supported in the upper portion of the fire-box *b* of a cooking-stove and provided with feet on its front and rear sides, formed to bear upon portions of the stove adjacent to the fire-box and support the receptacle in the upper portion of the fire-box, so that the fire will be in relatively close proximity to the top of the stove.

The bottom of the receptacle *a* is composed of bars *a'*, separated by suitable spaces, forming a grate, and the sides are preferably of grated or open-work form, as shown in the drawings. The horizontal top bar *a*² of the

rear side of the basket is depressed below the top bar *a*³ of the front side of the basket, so that the rear side of the basket is lower than the front side to permit the products of combustion to pass freely from the receptacle

are usually conducted from the fire-box over the oven of the stove.

The feet which support the receptacle may be of any suitable construction and arrangement. In the construction here shown the rear top bar *a*² is provided with two rearwardly-projecting feet *a*⁴ *a*⁴, which are constructed to be horizontally extended or contracted, as clearly shown in Fig. 1. The front top bar *a*³ is provided with forwardly-projecting ears *a*⁵ *a*⁵, with which are engaged vertical rods *a*⁶ *a*⁶, to the lower ends of which is secured a footpiece *a*⁷, the latter being vertically adjustable by means of the rods *a*⁶, which for this purpose may be screw-threaded and provided with suitable nuts to permit the vertical adjustment of the footpiece *a*⁷ and hold it at any position to which it may be adjusted. The feet *a*⁴ in the present instance bear upon the upper edge of the rear fire-brick lining *c*, and the foot *a*⁷ bears upon the upper edge of the front fire-brick lining *d*. The adjustability of the feet *a*⁴ enables the attachment to be adjusted to various widths of fire-box, and the vertical adjustability of the foot *a*⁷ adapts said foot to the height of the supporting-shoulder at the front of the fire-box whatever may be the distance between said shoulder and the top of the stove.

I do not limit myself to the details of construction here shown and may variously modify the same without departing from the spirit of my invention.

If desired, the ends of the receptacle may have telescopic or adjustable feet *a*⁸ to bear on projections at the ends of the fire-box, said feet *a*⁸ being designed for use in conjunction with the feet *a*⁴ and *a*⁷ when the structure of the stove renders it desirable that such feet *a*⁸ be employed for steadyng the receptacle or for any other purpose.

The foot *a*⁷ may have adjustable extensions *a*⁹ for use in stoves having unusually-wide fire-boxes.

It will be seen that the structure is such that it may be applied to the fire-box of almost any stove without regard to the size of said fire-box, and this may be done without varying the size of the basket-like receptacle. In other words, the front, end, and rear walls

of the receptacle are integral with the bottom, thus avoiding any possibility of any coming apart of sections and dumping of the fire contained therein, and at the same time the supports for the receptacle are adjustable, so as to permit it to rest easily upon the top of the fire-brick lining in such position that the entire structure can be readily removed by lifting after removing the top of the stove.

10 I claim—

1. A fuel-receptacle having a grated bottom and provided with horizontally-adjustable rear projections extending rearwardly from the rear of the receptacle below the plane of the top of the front thereof, and a vertically-adjustable front support extending forwardly from the front of the receptacle.

2. A fuel-receptacle having a grated bottom and provided with horizontally-adjustable rear projections extending rearwardly from the rear of the receptacle below the plane of the top of the front thereof, front projections

extending forwardly from the front of the receptacle, a footpiece below the said front projections, and adjustable connections between said footpiece and the front projections, whereby the distance between the footpiece and the front projections may be varied.

3. A fuel-receptacle having a grated bottom and provided with horizontally-adjustable projections extending rearwardly from the rear of the receptacle below the plane of the top of the front thereof, ears extending forwardly from the front of the receptacle, vertical rods adjustably connected with said ears, and a footpiece connected with the lower ends of said rods, for the purpose described.

In testimony whereof I have affixed my signature in presence of two witnesses.

CHARLOTTE D. ORCUTT.
